UNITED STATES PATENT OFFICE.

HERMANN DEUTSCH, OF GROSS-LICHTERFELDE, NEAR BERLIN, GERMANY, ASSIGNOR
TO PRINTATOR G. M. B. H., OF BERLIN, GERMANY.

MACHINE FOR PRINTING PRICE CARDS, TICKETS, LABELS, TAGS, AND THE LIKE.

Application filed October 28, 1921. Serial No. 511,109.

To all whom it may concern:

Be it known that I, HERMANN DEUTSCH, residing at No. 11 Marienplatz, Gross-Lichterfelde, near Berlin, Germany, have invented 55
certain new and useful Improvements in
Machines for Printing Price Cards, Tickets, Labels, Tags, and the like, of which the following is a specification.

The present invention relates in general to
machines for printing price cards, tickets, tags, information and visiting cards and the like as described in the United States Patent 60
No. 1,115,380. The invention relates more particularly to improvements in such machines which enable impressions to be printed on price cards, tickets, etc., in two or more colors without diminishing the speed of operation of the machine. An important feature of the invention consists in an inking gear with two or more collateral ink feeding and distributing devices, and a plurality of collateral inking rollers arranged in a common movable frame and adapted to impart ink in stripes of different colors to the stereotype printing plate or cliché.

Another important feature of a machine constructed in accordance with the invention resides in the provision of spring ink-spreading plates for spreading the ink fed from the ink reservoir and of ink-spreading rollers that are made to travel over the said plates and to impart the ink to the inking plates or disks from which the inking rollers receive the ink.

A further feature of the machine according to the invention may consist in the fact that the outlets through which the ink is fed from the ink reservoir, instead of leading straight to the bottom surface of the ink-spreading plate, are arranged to pass into a chamber of small capacity that extends across almost the entire breadth of the said plate and that is connected to the bottom surface of this plate by a narrow transverse slot. By this means the ink that leaves the reservoir is immediately caused to spread over the entire operating breadth of the ink-spreading plate so that the ink-spreading or ink-conveying rollers that travel along the bottom surface of this plate have ink fed onto them through the slot along their entire lengths so that the ink is already distributed evenly over their pe-

ripheries before they convey or transfer it to the inking disks. By this means the operation of transferring the ink to the inking disks is greatly improved.

A constructional form of a machine equipped with an inking gear according to the invention is illustrated in the drawing 65
in which—

Fig. 1 is a vertical longitudinal section on the line I—I of Fig. 2,

Fig. 2 is a ground plan of the inking gear in its normal position,

Fig. 3 is a similar view to Fig. 2 except that the ink rollers are shown in the position they occupy at the end of an ink-conveying operation.

Fig. 4 is a partial longitudinal vertical 70
section of an inking gear corresponding to Fig. 1 but with a modified ink feeding device.

Fig. 5 is a bottom plan view and

Fig. 6 a sectional partial top plan view 75
of Fig. 4 taken on the line VI—VI of Fig. 4.

The inking gear shown in Figs. 1 to 3 comprises a bed *a* in which a frame *c* is arranged to be reciprocated by a suitable driving member *b*. As the inking gear is intended to impart two different colored inks to the printing plate, two collateral pairs of inking rollers *d*, *d'* are journalled in the frame *c*. In addition to the inking rollers *d*, *d'* the frame *c* carries two ink-spreading and 85
ink-conveying rollers *e*, *e'*. At one end of the frame there is a transverse beam *f* and pivotally attached to this beam is a ratchet stepping finger *g* adapted to step round the inking disks *h*, *h'* as will be hereinafter more 90
fully described. The horizontal inking disks *h*, *h'* are arranged in the bed *a* of the machine so as to lie in the path of the rollers *e* and *d*, and *e'* and *d'*, and their height may be altered between certain limits by set 95
screws *i*, whereby the pressure exerted on them by the rollers *d*, *d'* and *e*, *e'* may be regulated. Each of the inking disks *h*, *h'* has a ratchet wheel *k*, *k'* associated with it, these wheels cooperating with pawls *l*, *l'* being pivoted to a transversely displaceable stepping bar *m* and held in engagement with the ratchet wheels *k*, *k'* by springs *p*. The stepping bar *m* is subjected to the pull of a spring which draws the bar in the direction 100
of the arrow *O*, Fig. 3. Projecting from

the stepping bar m is an arm q from which a tappet r protrudes that cooperates with the ratchet stepping member or finger g .

Loosely attached to the cover plate s of the inking gear and in the path of the top sides of the rollers e, e' are two rectangular ink-spreading plates t and t' respectively whose ends are pressed downward by leaf springs u which are also attached to the cover plate s . The ink reservoirs v, v' , which are constructed in any suitable manner and filled with inks of different colors, have mouths that pass through the ink-spreading plates t, t' .

15 The mode of operation of the illustrated inking gear is as follows:

When the machine is at rest the parts of the inking gear are in the position shown in Fig. 1 and a drop of liquid ink will be formed at the point of exit of the mouth of each ink reservoir v, v' . On the frame c now being moved in the direction of the arrow w from the position shown in Fig. 2 into the position illustrated in Fig. 2 the drops of ink emerging from the reservoirs v, v' will be spread over the bottom surfaces of the ink-spreading plates t, t' by the rollers e, e' which, after spreading the ink over the plates t, t' and over themselves, transfer it to the inking disks h, h' when they are advanced so as to roll along the surfaces of the said disks. As separate springs u are provided at both ends of the plates t, t' , the pressure between these plates and the rollers e, e' at the first and last moments of contact between the rollers and plates will be smaller than when the rollers are intermediate between the ends of the said plates. This is conducive of a satisfactory inking of the rollers e, e' . While the ink-conveying rollers e, e' convey new ink to the inking plates h, h' the inking rollers d, d' transfer the differently colored printing inks from the disks h, h' to the stereotype plate x which is arranged in the printing head of the machine and which thus receives the ink in two stripes of different colors. Each time the frame c is advanced, a slight rotary motion is imparted to the inking disks h, h' by the stepping pawls l that engage with the ratchet wheels, the stepping pawls being moved in a transverse direction along with the beam m which has transverse motion imparted to it by the finger g whose one lateral edge brushes against the tappet r and thus moves it in the direction of the arrow y , Fig. 2. When the frame c has reached the end of its advance stroke as indicated in Fig. 3 it is moved back to its normal position (Figs. 1 and 2) by the driving member b and this results in the ratchet stepping bar m being moved in the direction of the arrow o by the spring n and it is thus restored to its initial position without the pawls l, l' imparting a reversed rotary movement to

the inking disks as the said pawls then glide over the teeth of the ratchet wheels h, h' . At each printing operation executed by the stereotype plate x inked in the above-described manner by the novel inking gear, 70 an impression with two adjacent differently colored portions is produced on the paper surface printed on. Now since the paper band on which the impressions are made in shifted through a distance of one half of 75 the width of the stereotype plate in the direction of the arrow z at each stroke of the machine, printed tickets are produced which are half as wide as the stereotype plate and bear two-colored impressions. 80

In the modified ink feed device shown in Figs. 4 to 6 and also indicated in Figs. 1 and 2 the exits 3 from the cylindrical ink reservoir, which is provided with a piston 2 , do not lead directly to the bottom surface of 85 the ink-spreading plate t , but into a long narrow chamber 7 of rectangular cross section formed in the base 5 of the reservoir. Inserted in the narrow chamber 7 is a bar 6 which is almost as wide as the chamber 90 itself and whose top surface is bevelled as shown in Fig. 4. A hollow space or chamber of triangular cross section is thus formed in the base 5 and this chamber is connected by a transverse slot 4 to the lower 95 surface of the ink spreading plate t . It will be obvious that the ink discharged from the ink reservoir v will first fill the entire chamber of triangular cross section and then 100 emerge gradually through the slot 4 that extends across the whole operating breadth of the ink-spreading plate. Hence when the ink-conveying rollers reciprocate the ink will be immediately spread over the entire 105 surface of the plate t and it will thus be evenly distributed over the entire cylindrical surface of the said rollers d .

I claim:—

1. In a machine for printing price cards, tickets, labels, tags and the like, an ink reservoir, an ink feeding device, an ink spreading roller, an inking plate, a ratchet wheel associated with said inking plate, a pawl adapted to engage said ratchet wheel, a carrier for said pawl, a tappet on said pawl carrier, an ink transferring roller, a printing plate, a guide way along which a paper band is moved beneath said printing plate, a reciprocating carrier for said ink spreading and ink transferring rollers, and a tappet shifting member on said reciprocating carrier whereby said pawl carrier is moved relative to said reciprocating carrier and the inking plate rotated. 110

2. In a machine for printing price cards, 125 tickets, labels, tags and the like, a plurality of ink reservoirs, collateral ink feeding devices, an ink spreading roller, collateral inking plates, ratchet wheels associated with said inking plates, pawls adapted to engage 130

5 said ratchet wheels, a common carrier for said pawls, a tappet on said pawl carrier, an ink transferring roller, a printing plate divided into collateral sections, a guide way along which a paper band is moved beneath the printing plate, a reciprocating carrier for said ink spreading and ink transferring rollers, and a tappet shifting member on said reciprocating carrier whereby said pawl carrier is moved relative to said reciprocating carrier and the inking plate rotated.

3. In a machine for printing price cards, tickets, labels, tags and the like, a stereotype printing plate divided into collateral sections, a guide way along which sections of a paper band are moved successively into registration with the different sections of the stereotype plate, reservoirs with inks of different colors, a support, collateral ink reservoirs for inks of different colors, collateral horizontal spring pressed plates attached and arranged beneath the said support, passages leading from the said reservoirs to the bottom surfaces of the said spring pressed plates, collateral inking plates, collateral ink-spreading rollers for spreading the ink that emerges from the said passages over the said spring pressed plates and over themselves and for conveying the ink to the said collateral inking plates, inking rollers for transferring inks of different colors from the inking plates to the different sections of the stereotype plate, and a reciprocating carrier for reciprocating all of the said rollers in 35 directions at right angles to the direction of movement of the said paper band.

4. In a machine for printing price tickets, labels, cards and the like, a stereotype printing plate, a guide way along which a paper band is moved beneath the printing plate, an ink reservoir, a support, a horizontal spring pressed ink-spreading plate depending from the said support, a passage leading from the said reservoir to the bottom surface of the 45 spring pressed plate, rollers for spreading the ink that emerges from the said passage over the spring pressed plate and for transferring it to the printing plate, and a reciprocating carrier for reciprocating the said rollers in directions at right angles to the direction of movement of the said paper band.

5. In a machine for printing price tickets, labels, cards and the like, a stereotype printing plate, a guide way along which a paper band is moved beneath the printing plate, an ink reservoir, a support, a horizontal ink-spreading plate depending from the said support, springs located at the ends of 55 the ink-spreading plates and adapted to press these ends downward, a passage leading from the said reservoir to the bottom surface of the ink-spreading plate, rollers for spreading the ink that emerges from 60 the said passage over the ink-spreading

plate, and for transferring it to the printing plate, and a reciprocating carrier for reciprocating the said rollers in directions at right angles to the direction of movement of the said paper band.

6. In a machine for printing price tickets, labels, cards and the like, a stereotype printing plate, a guide way along which a paper band is moved beneath the printing plate, an ink reservoir, a support, a horizontal spring pressed ink-spreading plate depending from the said support, a passage leading from the said reservoir to the bottom surface of the spring pressed plate, an inking plate, an ink-spreading roller for spreading the ink that emerges from the said passage over the spring pressed plate and over itself and for conveying the ink to the said inking plate, an inking roller for transferring the ink from the inking plate to the printing plate, and a reciprocating carrier for reciprocating the said rollers in a direction at right angles to the direction of movement of the said paper band.

7. In a machine for printing price tickets, labels, cards and the like, a stereotype printing plate, a guide way along which a paper band is moved beneath the printing plate, an ink reservoir, a support, a horizontal ink-spreading plate depending from the said support, a passage leading from the said reservoir to the bottom surface of the spring plate, an inking plate, an ink-spreading roller for spreading the ink that emerges from the said passage over the ink-spreading plate and over itself and for conveying the ink to the said inking plate, an inking roller for transferring the ink from the inking roller to the printing plate, a reciprocating carrier for reciprocating the said rollers in a direction at right angles to the direction of movement of the said paper band, and a ratchet and pawl mechanism for rotating the inking plate.

8. In a machine for printing price tickets, labels, cards and the like, a stereotype printing plate, a guide way along which a paper band is moved beneath the printing plate, an ink reservoir, a support, a horizontal spring pressed ink-spreading plate depending from the said support, a passage leading from the said reservoir to the bottom surface of the spring pressed plate, an inking plate, an ink-spreading roller for spreading the ink that emerges from the said passage over the spring pressed plate and over itself and for conveying the ink to the said inking plate, an inking roller for transferring the ink from the inking roller to the printing plate, a reciprocating carrier for reciprocating the said rollers in a direction at right angles to the direction of movement of the said paper band, a ratchet wheel associated with the inking plate, a pawl adapted to engage with the ratchet wheel, a pawl carrier adapted to 130

reciprocate transversely to the said reciprocating roller carrier, a tappet on the pawl carrier, and a tappet shifting member associated with the roller carrier.

zontal ink-spreading plate depending from 50
the said support, a transverse groove of rect-
angular cross-section in the bottom of the
said ink-spreading plate, a bevelled strip ar-
ranged with its sloping surface uppermost
in the said groove so as to form an ink-con- 55
tainer of small capacity, extending across
the ink-spreading plate, a passage leading
from the ink-reservoir to the ink-container, a
transverse slot in the ink-spreading plate for
conducting ink from the said container to 60
the bottom of the said plate, rollers for
spreading the ink that emerges from the said
passage over the ink-spreading plate and for
transferring it to the printing plate, and a
reciprocating carrier for reciprocating the 65
said rollers in directions at right angles to
the direction of movement of the said paper
band.

12. In a machine for printing price cards, tickets, labels, tags and the like, a stereotype printing plate divided into collateral sections, a guide way along which sections of a paper band are moved successively into registration with the different sections of the stereotype plate, reservoirs with inks of different colors, a support, collateral horizontal plates depending from the said support, collateral ink-containers of small capacity extending across the ink-spreading plates, passages leading from the ink reservoirs to the ink-containers, transverse slots in the ink-spreading plates for conducting ink from the said containers to the bottom surfaces of the said plates, collateral rollers for spreading the inks that emerge from the said passages over the plates and for transferring them to the sections of the printing plate, and a reciprocating carrier for reciprocating the said rollers in directions at right angles to the direction of movement of the said paper band. 70 75 80 85 90

In testimony whereof I have signed this specification in the presence of two witnesses.

HERMANN DEUTSCH.

Certificate of Correction.

It is hereby certified that in Letters Patent No. 1,493,810, granted May 13, 1924, upon the application of Hermann Deutsch, of Gross-Lichterfelde, Germany, for an improvement in "Machines for Printing Price Cards, Tickets, Labels, Tags, and the Like," an error appears in the printed specification requiring correction as follows: Page 4, line 77, claim 12, before the word "plates" insert the compound word *ink-spreading*; and that the said Letters Patent should be read with this correction therein that the same may conform to the record of the case in the Patent Office.

Signed and sealed this 15th day of July, A. D. 1924.

[SEAL.]

THOMAS E. ROBERTSON,
Commissioner of Patents.
